UNITED STATES PATENT OFFICE.

WILLIAM DANIEL HUFF, OF LA FAYETTE, LOUISIANA, ASSIGNOR OF THREE-FOURTHS
TO LOUISE GUIDEY MOSS, OF NEW IBERIA, LOUISIANA.

CLEANING OIL-WELLS.

1,169,261.

Specification of Letters Patent. Patented Jan. 25, 1916.

Original application filed April 6, 1915, Serial No. 19,607. Divided and this application filed April 28, 1915.
Serial No. 24,463.

To all whom it may concern:

Be it known that I, WILLIAM D. HUFF, a citizen of the United States, residing at La Fayette, in the parish of Lafayette and State of Louisiana, have invented certain new and useful Improvements in Cleaning Oil-Wells; and I do hereby declare the following to be a full, clear, and exact description of the invention, such as will enable others skilled in the art to which it appertains to make and use the same.

In my Patent No. 1140982, granted May 25, 1915, and entitled improvements in operating oil wells, I have described a process and apparatus for lifting the contents of the well by means of the gaseous pressure generated in the well casing by heating up the liquid contents occurring in the bottom of said casing, and causing the steam and other gases so generated to flow through ejector nozzles provided in an inner pipe in the well casing, causing the liquid to flow from the bottom of the well up through said inner pipe and out at the surface, as fully described in the application aforesaid.

In the same patent I have described as a part of the operation of the oil well in the manner stated, the use of the apparatus for carrying out the process of cleansing the well and the well screen, and for thinning the oil and promoting the flow of the oil from the well at such times as the well and its screen may need cleansing. In this process of cleansing the well and its screen, I temporarily suspend the action of the ejector, and heat up the liquid in the well to such a temperature as to generate sufficient gaseous pressure to force the heated liquid through the screen back into the oil-bearing strata of the well. This will heat up the strata and will thin the oil, and melt any paraffin, or similar ingredients, which tend to thicken the oil and retard its flow, and incidentally will also cleanse the screen by causing a flow of hot liquid out through the screen.

If a single discharge of heated liquid from the bottom of the well casing out through the screen and into the oil-bearing strata is not sufficient, the pressure may be removed and liquid may be permitted to flow back into the well casing, when the process of heating up the liquid in the well casing and

discharging it back into the oil-bearing strata may be repeated a sufficient number of times to insure the thorough cleansing of the well, and incidentally, a thorough cleansing of the screen.

This process, while described in the patent aforesaid, was not claimed therein, being for a separate invention from the lifting process which was claimed in said application, and is more fully described and claimed herein; this being a division of the application aforesaid.

My invention will be more clearly understood by reference to the accompanying drawings, in which the same parts are indicated by the same reference symbols throughout the several views.

Figure 1 shows a section through the well casing and well, with the inner tube in elevation, and the electric heating arrangement shown diagrammatically, parts being broken away; Fig. 2 shows a central vertical section through the ejector, but on a larger scale than in Fig. 1; Fig. 3 shows a section along the line 3—3 of Fig. 2, and looking down; and Fig. 4 shows, on a larger scale, the head of the well casing and connected parts.

The well casing 1 is preferably constructed in the usual way forming a gas-tight hollow cylindrical well, perforated only toward the bottom as at 2; but instead of the perforations 2, a suitable strainer, such as is well known in the art, may be used if desired.

The top section of the casing is perforated, as at 3, to receive the relief pipe 4 carrying the relief valve 4^a, the pressure gage 5, and a suitable safety valve 6.

The upper end of the casing is screw-threaded, as at 7, to engage the screw cap 8 beneath which is preferably placed a suitable packing 9. This cap is provided with a suitable stuffing box 10, through which passes the inner pipe 11, which inner pipe is also made up in the usual way of a series of sections connected together, and the lower section or sections of the pipe are preferably perforated, as at 12, to permit the flow of said liquid into said pipe from the interior of the casing 1. The upper portion of this inner pipe 11 terminates in a delivery pipe 14 for carrying the liquids

delivered from the well to any desired receptacle, not shown, and this pipe 14 is controlled by a valve 15.

I provide on the interior of the casing 5 suitable heating devices such, for instance, as electric heaters 21, which are preferably cylindrical in shape and surround the inner pipe 11, as shown. Any suitable heater, whether electric or of other construction, 10 may be used in this connection; and I do not claim any special form of heater as part of my invention. The electric heaters shown are supplied with electricity from the individual feed wires 22, which are bound up 15 in a suitable insulated cable 23, which cable is secured to the inner pipe in any convenient way, as by the strips 24. This cable passes up through a plug 25 in the well casing, and the individual conductors are connected to separate switches located in the 20 switchboard 26, each of which switches is adapted to make connection with the main 27 which is supplied with electricity from any suitable source, as the dynamo 28. The 25 return main 29 is grounded in any convenient way, preferably by connecting same to the inner pipe 11, as shown in Fig. 1, thus providing an all-metallic circuit for the electricity.

30 Between the mains 27 and 29 a suitable voltmeter, indicated by V, is preferably provided, and suitable resistance coils and ammeters A may be provided for each switch, as shown in Fig. 1. The electric 35 connections are shown diagrammatically in said figure, but the apparatus is intended to provide means for heating each electric coil, and for regulating the temperature of each coil, independently of all the others.

40 I provide a suitable ejector for use on the well known principle of such apparatus, comprising a short bulbous connection 40 between the adjacent lengths of the inner pipe 11, which connection is attached to the 45 upper portion of the inner pipe 11 in any convenient way, as by the coupling 41; and mounted in the upper end of this bulbous connection 40 is the upper nozzle 43 of the ejector, which upper nozzle is provided 50 with a conical chamber, into which projects the upper end of the inlet nozzle 45, as shown most clearly in Fig. 5. This lower nozzle should be preferably steadied in the connection 40, and I have shown a spider 55 46 used for this purpose, which spider is preferably made three-legged in order to be conveniently slipped into place in the connection 40, and may be held in place in any convenient way, as by the screw bolts 47. 60 Any suitable mode of mounting the ejector may be employed.

To raise and lower the inner tube in the well, a suitable hoist 50 may be attached to the top of said tube; and the raising and 65 lowering may be accomplished by the appa-

ratus (not shown) installed when the well is bored and used in handling the pipes.

In oil wells there is nearly always more or less water, and in those wells that require pumping, or in old or abandoned 70 wells, there is often considerable water to be removed before the well can be caused to deliver the crude oil properly.

In the operation of the device, the first point is to determine the depth below the 75 surface of the ground of the static head X—X of the liquid in the well; this may be done by a floating plummet introduced into the well before the cap is put on, as is well known in the art. Having determined the 80 depth of the static head, and incidentally the height the liquid is to be raised above the static head, I submerge the ejector to a point sufficiently below the static head to require adequate pressure to be generated in 85 the casing to depress the level of the liquid therein below the location of said ejector, in order to give pressure sufficient to cause the ejector to lift the column of liquid in the inner tube to the surface of the ground. 90 Suppose, for instance, the static head to be 400 feet below the surface of the ground, and assuming the casing to be strong enough to stand an internal pressure of say 400 pounds per square inch, the ejector inlet 95 should preferably be about 1200 feet below the surface of the ground. Then the cap of the well being closed, and the electric connections made, electricity is turned on to operate the submerged heaters, with the result that the liquid in the well casing is heated and steam and hydrocarbon gases are generated, which steam and other gases will rise up through the liquid and accumulate in the top of the well casing, forcing the liquid down in said casing from the level indicated at X—X, or static head, to a point below the inlet opening of the 100 ejector.

When there is only water in the well casing, steam, of course, will be the only gas generated, and hereinafter whenever the words "gas", or "gas pressure", or "gaseous pressure," are used, I mean to include in these generic terms "steam" and "steam pressure"; and in the same way I mean by the term "liquid" to include water and such other liquid or semi-liquid composition or mixtures of matter as are found in wells of 115 the character described.

When the surface of the liquid falls below the inlet opening 48 of the inlet nozzle 45, there will be a rush of steam, and generally other gases, under pressure through said nozzle and up through the upper nozzle 43 which will enter the column of liquid in the inner pipe above said upper nozzle and cause an upward flow of the liquid in the upper portion of the inner pipe 11.

In addition to the dynamic effect of the 130

rapid inrush of gases into the ejector, the steam, and other gases, entering the column of liquid above the nozzle 43 will also tend to promote the upward flow of the column of liquid above the nozzle 43 under the well known principle of the aerial column, as shown, for instance, in the patents to J. G. Pohle, entitled process of elevating liquids, No. 487639, granted December 6, 1892, and No. 532699 for process of and apparatus for elevating liquids, granted January 15, 1895. Furthermore, the mixture of liquid and gas will be lighter than a similar column of liquid alone, and the pressure required to lift the superposed column in the inner pipe will be materially decreased.

Suitable heaters may be provided along the length of the inner pipe 11 above the ejector, whereby a high temperature of the liquid, and more especially of the gases contained therein, may be secured, with the result that the buoying-up effect of the gases may be materially increased.

If there be free liquid connection between the oil-bearing strata of the well and the screen and bottom of the well casing, as in free flowing wells, the height of the liquid in the inner tube will remain constant, corresponding to the normal static head of the well, irrespective of the gas pressure in the well casing, until the gas can get into the ejector nozzle; but should the flow of the well be slow and the gas pressure be suddenly raised there would be a lifting of the column in the inner tube to balance the excess gas pressure in the casing, which might under certain circumstances be sufficient to cause the liquid to flow out of the top of the inner tube; but this lifting of the inner column of liquid by pressure alone will have no other effect than the advantageous one of facilitating the starting up of the operation after the gas gets below the inlet nozzle of the ejector, when the operation under the ejector principle becomes continuous, and commensurate with the flow of oil into the bottom of the well. It will be obvious that the actual height the liquid has to be raised is determined by the depth of the normal static head of the well below the surface of the ground.

The operation of the apparatus as hereinbefore described will continue indefinitely as long as the flow of oil continues through the screen, near the lower end of the casing, and adequate pressure is maintained in the upper end of the casing above the liquid therein. But should the flow of oil through the screen be diminished, due to the thickening of the oil in the oil-bearing strata, the clogging up of the screen, or other causes, and it be necessary or advisable to warm and consequently thin the consistency of the oil in the region surrounding the screen, or to cleanse the screen by sending

a reverse current of hot liquid therethrough, the valve 15 is closed, and the pressure is permitted to escape from the casing through the valve 4^a, permitting the liquid in the casing to assume the normal static head. 70 Then close the valve 4^a and heat the column of liquid in the well casing to a temperature high enough to generate sufficient gaseous pressure in the upper part of the casing to force a portion of the heated liquid inclosed 75 in the casing back through the screen and into the oil strata, heating the same and thinning the oil, and incidentally cleaning the screen.

It will be noted that the liquid in the well 80 casing must be heated considerably above 212° F. to secure gaseous pressure enough to force the level of the liquid down any material distance against the upward pressure due to the normal static head, and thus 85 the liquid forced out of the well casing back into the oil-bearing strata will be quite hot when it flows outward through the screen.

If a single discharge of the heated liquid in the casing back through the screen and 90 into the oil-bearing strata be not sufficient, this heating process can be repeated until the strata are adequately heated to permit the free flow of the oil in the well again.

Of course, the flow of heated liquid outward through the screen will tend to cleanse the screen by washing away the solid particles, muds, etc., that may have accumulated on the outside of the screen, and also will dissolve or liquefy many of the viscous or 100 semi-viscous products of the well, such as paraffin, etc., that may have clogged the screen and retarded, or prevented, the free flow of liquid therethrough.

Should the pressure in the well outside 105 the casing decrease sufficiently from any cause, the hot water ejected would, of course, liberate large quantities of steam which would penetrate and condense in the crevices in the strata and rapidly warm same; and a 110 similar result would be secured as soon as the level of the hot liquid in the casing was forced, by pressure, below the top of the screen, or perforations, in the well, at which time the steam would rush out through the 115 openings in the side of the well casing and permeate and condense in the earth strata, rapidly warming the same.

When the oil again flows freely, the valve 15 is opened and process of ejecting the liquid is resumed.

This heating and cleaning of the screen and oil strata may be performed as often as found necessary.

Generally oil wells, especially when they 125 need cleaning, or flow slowly, or not at all, contain more or less water or oil, or both, in the lower part of the casing; and for the purpose of flushing the strata with heated liquid, and washing the strainer by forcing 130

this heated liquid out therethrough, this normal source of liquid supply will ordinarily suffice. But, under certain conditions, it may be desirable to furnish more liquid, 5 or even a complete supply of water to the well chamber to carry the heat back into the well strata; and this can be done by connecting either the pipe 4 or the pipe 14 to any suitable source of water or oil supply. It 10 is preferable to use crude oil for the purpose, as it has substantially the same specific gravity as the liquid in the well. Thus liquid may be pumped or allowed to run by gravity into the well until it rises to the required height in the casing. Then this liquid 15 may be heated, generating steam or other gaseous pressure above same, as before described, and the heated liquid may be forced by this pressure down the casing and out 20 through the screen in the same manner as if the liquid had flowed in from the strata of earth in the usual way.

It may be desired, in certain cases, to raise or lower the inlet 48 of the ejector to suit 25 varying conditions of the flow of liquid in the well, such, for instance, as are occasioned by the lowering of the natural static head of the liquid in the well. This may be accomplished in various ways, for instance, by 30 using the derrick arrangement, not shown, employed in constructing the well and by attaching the hoist 50 to the inner pipe 11, and thereby raising or lowering said pipe.

While I have shown in this divisional application the complete apparatus described and claimed in my Patent #1,140,982, aforesaid, it will be obvious that this cleansing of the well and its screen by generating pressure therein is not necessarily limited to apparatus 35 in which the liquid is lifted from the well by an ejector; and the herein described process may be used with other forms of apparatus, in which the oil escapes from the well either by the natural pressure, or is pumped or lifted out by other means 40 than the ejector herein shown, but I prefer to use, in carrying out the herein described process, the apparatus described in my patent aforesaid for the reason, primarily, that the same apparatus which provides the heat 45 and gaseous pressure for operating the ejector, also provides the heat and gaseous pressure for operating the process hereinafter claimed. While the two processes are in a sense independent of each other, it being impracticable with the same apparatus to carry out the two processes simultaneously, at the same time the processes are closely related in that the flow of liquid into the well is promoted 50 at one step, and after this flow becomes continuous the same apparatus will generate the gaseous pressure required to lift the liquid out of the well; but I do not mean to limit myself to any particular ap-

paratus for carrying out the herein described process.

While I have shown herein the preferred form of apparatus, and have described the method of operating the same, it will be obvious that various modifications, both in the apparatus and in the mode of operation, may be employed which could be used without departing from the spirit of my invention, and I do not intend to limit myself to details of construction and operation, except such as are specifically set forth in the claims.

Having thus described my invention, what I claim and desire to secure by Letters Patent of the United States is:—

1. The method of operating oil wells provided with a gas-tight casing having a closed top and a screen in the lower portion thereof, and a central delivery pipe and an injector therein inclosed in said casing, with means for closing said pipe, which consists in applying sufficient heat to the liquid in the lower end of said casing to generate therefrom gaseous pressure in said casing, which rising in said casing above said heated liquid will force part of the liquid so heated back through said screen into the oil-bearing strata, thereby warming same and thinning the oil, and incidentally cleansing said screen, in then relieving said pressure and allowing the well to resume its flow, and finally lifting the liquid flowing from the well into the bottom of said casing by means of gaseous pressure flowing through said injector, said gaseous pressure being generated by heating part of the liquid contained in said casing, substantially as described.

2. The method of operating oil wells provided with a gas-tight casing having a closed top and a screen in the lower portion thereof, and a central delivery pipe and an injector therein inclosed in said casing, with means for closing said pipe, which consists in applying sufficient heat to the liquid in the lower end of said casing to generate therefrom gaseous pressure in said casing, which rising in said casing above said heated liquid will force part of the liquid so heated back through said screen into the oil-bearing strata, thereby warming same and thinning the oil, and incidentally cleansing said screen, and in then relieving said pressure and allowing the well to resume its flow, and in repeating said operation of heating the liquid in the casing, generating pressure, and causing said pressure to discharge the liquid from said casing back into the oil-bearing strata until the latter are sufficiently warmed to secure the proper flow of oil therefrom, and finally lifting the liquid flowing from the well into the bottom of said casing by means of gase-

ous pressure flowing through said injector, said gaseous pressure being generated by heating part of the liquid contained in said casing, substantially as described.

- 5 3. The method of cleansing oil wells provided with a gas-tight casing having openings in the lower portion thereof, and a closed top, and means for supplying liquid therethrough; which consists in supplying 10 liquid through said top to the interior of said casing, in applying sufficient heat to the liquid in the lower end of said casing to generate therefrom gaseous pressure in said casing, which rising in said casing above 15 said heated liquid will force part of the liquid so heated, and also part of the steam and other gases so generated, back into the oil-bearing strata, thereby warming same and thinning the oil, and in then relieving 20 said pressure and allowing the well to resume its flow, substantially as described.
4. The method of cleansing oil wells provided with a gas-tight casing having openings in the lower portion thereof, and a 25 closed top, and means for supplying liquid therethrough, which consists in supplying liquid through said top to the interior of said casing, and in applying sufficient heat to the liquid in the lower end of said casing 30 to generate therefrom gaseous pressure in said casing, which rising in said casing above 35 said heated liquid will force part of the liquid so heated, and also part of the steam and other gases so generated, back into the oil-bearing strata, thereby warming same and thinning the oil, and in then relieving 40 said pressure and finally lifting the liquid 45 from said casing after the well resumes its flow, by an injector operated by gas pressure generated from the liquid that has 50 flowed into the well, substantially as de- 55 scribed.
5. The method of operating oil wells provided with a gas-tight casing having openings in the lower portion thereof, and a 55 closed top, and means for supplying liquid therethrough which consists in supplying liquid through said top to the interior of 60 said casing in applying sufficient heat to the liquid in the lower end of said casing to generate therefrom gaseous pressure in said casing, which rising in said casing above 65 said heated liquid will force part of the liquid so heated, and also part of the steam and other gases so generated, back into the oil-bearing strata, thereby warming same and thinning the oil, and in then relieving 70 said pressure and allowing the well to resume its flow, substantially as described.

the well to resume its flow, and in repeating said operation of supplying fresh liquid through the top of said casing, heating the liquid in the casing, generating pressure, and causing said pressure to discharge the liquid from said casing, and also part of the steam and other gases so generated, back into the oil-bearing strata until the latter 40 are sufficiently warmed to secure the proper flow of oil therefrom, substantially as described.

5. The method of operating oil wells provided with a gas-tight casing having openings in the lower portion thereof, and a closed top, and means for supplying liquid therethrough which consists in supplying liquid through said top to the interior of said casing in applying sufficient heat to the liquid in the lower end of said casing to generate therefrom gaseous pressure in said casing, which rising in said casing above 55 said heated liquid will force part of the liquid so heated, and also part of the steam 60 and other gases so generated, back into the oil-bearing strata, thereby warming same and thinning the oil, and in then relieving 65 said pressure and finally lifting the liquid 70 from said casing after the well resumes its flow, by an injector operated by gas pressure generated from the liquid that has flowed into the well, substantially as de- 75 scribed.

In testimony whereof, I affix my signature.

WILLIAM DANIEL HUFF.
